UNITED STATES PATENT OFFICE.

JOSEPH M. GARDINER, OF BALTIMORE, MARYLAND.

LOOSE-LEAF BINDER.

Application filed March 14, 1921. Serial No. 452,073.

To all whom it may concern:

Be it known that JOSEPH M. GARDINER, a citizen of the United States, residing at Baltimore, in the State of Maryland, has 5 invented certain new and useful Improvements in Loose-Leaf Binders, of which the following is a specification.

This invention relates to improvements in loose leaf binders or holders and has for 10 one of its objects to provide improved post and pin structures whereby the same may be lengthened or shortened as the number of sheets added to or removed from the binder renders such variation in the length of the 15 posts and pins necessary or desirable.

Another object of the invention is to provide an improved construction of sectional post and pins whereby the same may be readily extended or shortened and to also 20 provide improved means whereby to lock the sections together and prevent longitudinal displacement.

A further object of the invention is to provide an improved construction of sectional 25 post wherein the same are of substantially a rectangular shape with fastening means extending through and clamping all the sections together and also having means to lock adjacent sections to prevent rotation of one 30 section with respect to the other.

The accompanying drawing illustrates the invention, wherein,

Fig. 1. shows a portion of a binder embodying the invention, the leaves adjacent 35 to the post being broken away to better illustrate the latter.

Fig. 2. illustrates the same in sectional end elevation.

Fig. 3. shows a vertical sectional detail 40 through the post with the locking means therein.

Fig. 4. illustrates the rigid post-part in top view.

Fig. 5. shows one of the detached post 45 units in perspective.

Fig. 6. illustrates the detached post locking-screw.

Fig. 7. shows a corner of one form of sheet or leaf with which the post is to coact 50 and secure.

Fig. 8. illustrates a tool employed to operate the locking-screw.

Figs. 9 and 10 show enlarged sectional and top views respectively of a post sec-

tion or unit embodying the invention but of 55 a slightly modified form, and

Fig. 11. illustrates a sectional detail through one of the sectional pins and its fastening means.

Referring to the drawing, the numeral 10, 60 designates the stationary clamping bar and 11, the removable clamping bar of a binder. Each clamping bar has a back 12, hinged thereto in the usual manner and the movable clamping bar 11, is provided on its interior 65 with a clamping mechanism which is operated by the rotation of a horizontal shaft 13, whose end is exposed at one end of the bar. All of these elements are well known, and are utilized in binders that are now 70 upon the market, and a detailed illustration of them is deemed unnecessary to an understanding of my present invention.

In carrying out my invention I provide the stationary clamping bar 10, with sheet- 75 engaging posts of an improved construction as will now be explained.

In practice the bar 10, is of a hollow construction and on the interior of the same I seat a short post-base 14, which latter, in 80 this instance, is rigidly secured to the bar by means of screws 15. In practice a plurality of these post-bases are employed, but only one is illustrated in the drawing.

The post-base 14 is substantially rectangular in cross-section, the corners however being preferably rounded, and as shown in Fig. 4, the top of the base is provided with a plurality of depressions or sockets 16, while a central vertical screw-threaded bore 17, 90 extends down into the base.

For each post-base I provide a sectional post structure which is made up of a series of sections or units 18 and an uppermost post-section 18'.

Each post section or unit has an exterior cross-sectional shape precisely like the exterior shape of the post-base, but some of the sections in the preferred form differ from the base in that they preferably have a vertical semi-circular slot extending therethrough from top to bottom which slot opens at one side.

At least the uppermost section of each post has an upper portion 19 of this slot, 105 that is of a greater area than its lower portion 20, so that a semicircular shoulder 21, is formed in a horizontal plane between

the upper and lower ends of the slot for a purpose presently to be explained.

The bottom of each post-section is provided with a plurality of downwardly-extending pins 22, while the top of each section is provided with a plurality of depressions or sockets 23.

When the sections are placed on top of the base-section 14 the pins 22 on the lower section will register with and enter the sockets 16 in the top of the base-section, while the recesses 23 in the top of each post section 18 will receive the pins 22 on the section next above it. The pins and recesses therefore lock the sections together to prevent rotation or lateral displacement of one section with respect to the other.

The slots through the sections 18 are smooth, or are free of screw-threads, and when one, two, three or more sections are placed one after another on top of a post-base, all of the slots will align with the central screw-threaded bore 17 in the post-base, as shown in Fig. 3, of the drawing.

The number of sections 18, may be increased as the addition of leaves or sheets 24, to the binder requires, as will presently be more fully explained.

It is therefore to be understood that with each binder in which my sectional posts are employed there will be provided a number of post-sections so that the post may be lengthened as the additional sheets placed in the binder may require.

With each binder I also provide a series of locking screws 25, which are alike in construction but which are formed in sets,—one set differing from another only in their length. As an example, if the binder is provided with four posts every set of locking screws may comprise four screws.

Each locking screw 25 has a screw-threaded body, an annular flange 26, at the upper end of the body, and a squared or angular head 27, so that a suitable wrench 28, having a socket 29, therein may be employed to rotate the screws.

The binder also employs a plurality of pins which according to my invention comprise a tubular base-pin 30, which is riveted or otherwise rigidly attached at 31 to the stationary bar 10 of the binder, as shown in Figs. 2 and 11 of the drawing.

The tubular base-pin, like the post-base 14, is rigid with the bar 10 and extends upwardly therefrom. The interior of this base-pin is provided with screw-threads 32 so that a bolt 33 may be screwed down into the tubular base-pin, as clearly shown in Fig. 11.

This bolt 33 has an enlarged head 34 at the upper end whose diameter is substantially equal to the external diameter of the tubular base-pin.

On top of the tubular base-pin I provide

a series of sleeves 35 and these sleeves are of an external size that corresponds with the external diameter of the tubular post and also the head 34 of the bolt.

It will thus be seen that the pins may be extended by the addition of sleeves 35, around the bolt and supported above the base pin while the head of the bolt will clamp the sleeves down and hold them in place.

By reference to Figs. 9 and 10 of the drawing it will be noted that the modified form of base-section 36 has a central slot 37 therethrough, and has the lower pins 22, and the upper sockets 23 just as in the preferred form. The only difference being that the shoulder 21 and open side to the slot are omitted in this modified form.

The character of sheets 24, employed in the binder is illustrated in Fig. 7, which shows the sheet with edge notches 37, and a perforation 38, between two notches.

The notches are shaped and sized to fit about or receive the post-sections while the perforations 38, permit the passage of the sectional pins.

In practice when the binder is first put into use the post bases 14, only may be used and the movable clamping bar 11 and its hinged back 12, will be removed,—the movable clamping bar being provided with suitable vertical slots through which the post-bases or the post-sections may project.

The sheets or leaves 24, will be placed on top of the lower lock part 12, and stationary bar 10,—the perforations 32, in the sheets being inserted over the pins 30, and the notches 37, embracing the post-bases 14. The clamping bar 11, and its lock are then placed on top of the sheets and the post-bases will project through the movable bar 11. When the bar 11 and lock 12, are in place the bar will be pressed down over the post-bases to compress the sheets between it and the bar 10, and while held in this position the wrench 28, will be engaged with the end of shaft 13, and the latter rotated which causes the clamping means in the bar 11, to engage the post-bases and hold the bar in locked position.

When the post-bases 14, are too short to allow more sheets to be placed in the binder, the clamping bar 11 and its lock 12, will be removed and one or more units or post-sections 18, or 36 will be placed on the end of each post-base and a locking screw 25 will be passed down through the central slots of each post-section, and screwed down into the threaded bore 17, of the post-base until the flange 26, seats on the semi-circular shoulder 21, in the post-section slot or on a washer that may be used when the sections 34 are employed. These post-sections as heretofore explained are held against rotation by the recesses 16 and 23.

and the pins 22, and when clamped by the screws 25 are rigid, and have the same effect as though they were integral with the post-bases.

5 The reason for utilizing the units or sections is, that when the binder is in use very little post-end projects beyond the movable clamping bar because only sufficient units are employed to clamp the sheets in 10 the binder, whereas if the posts are made long enough to accommodate all the sheets the binder may hold at any one time, then the posts would project so far beyond the clamping bar 11, as to materially interfere 15 with the practicability of the binder when the latter is spread open like a book.

Having described my invention, what I claim is,—

1. In a loose leaf binder the combination 20 with two clamping bars each carrying a hinged back, of post bases attached to one of said bars, detachable post sections designed to be mounted on each post-base, means for locking the sections to prevent the 25 rotation of one with respect to the other or with respect to the post-base and means extending down through the sections into the base to lock all the sections down on the base said latter means being independent of the 30 locking means that prevents rotation.

2. In a loose leaf binder the combination 35 with two clamping bars each carrying a hinged back, of post bases attached to one of said bars, detachable post sections designed to be mounted on each post-base, means for locking the sections against rotation with respect to the post-base and means for rigidly securing the sections to the base.

3. In a loose leaf binder the combination 40 with two clamping-bars, of sectional posts extending between said bars, a screw extending vertically through the sections and engaging the lowermost section for locking the sections together and means independent of 45 the screw for locking the sections against independent rotation.

4. In a loose leaf binder the combination 50 with two clamping-bars, of post bases attached to and projecting from one of said bars, each post-base having a screw-threaded socket therein, post-sections for each post-base and each section having a central opening therethrough and of the same cross-sectional shape as the post base, a bolt extending 55 down through the central openings of the sections and engaging the threads in the socket of the base whereby to lock the sections on the base and projecting means on each section to engage a recess in another or 60 in a post base to lock the sections against independent rotation.

5. In a loose leaf binder the combination 65 with two clamping-bars, of post bases attached to and projecting from one of said bars, each post-base having a screw-thread-

ed socket therein, post-sections each having a central opening therethrough and of the same cross-sectional shape as the post base and the uppermost section having a shoulder in its central opening and a bolt passing 70 down through the section openings and screwing into the socket in the base and the upper end of the bolt engaging the shoulder in the central opening of the uppermost section. 75

6. In a loose leaf binder the combination with two clamping bars, of post-bases attached to and projecting from one of said bars; post-sections on top of the post bases and having openings therethrough and the uppermost section being provided with a shoulder in its opening, and means extending 80 down through the sections and bearing on the shoulder of the uppermost section and engaging the post-base for locking the sections and base together. 85

7. A sectional post for loose leaf binders comprising a base section having a threaded bore therein, a series of post-sections each having a vertical opening extending therethrough, a locking screw passing through the openings of the sections and entering the bore of the base,—said screw having a head on its outer end which head has a diameter equal to the exterior diameter of both the 90 base and post sections. 95

8. A sectional post for loose leaf binders comprising a base section having a threaded bore therein, a series of post-sections having a vertical opening extending therethrough and the uppermost section having a shoulder in said opening and a locking screw having a flange to seat on the shoulder in the opening of the uppermost post section and said screw passing down into the threaded bore of the base-section. 100 105

9. A sectional post for loose leaf binders comprising a base section having a threaded bore therein, post-sections on top of the base and some of said post-sections having a slot extending vertically therethrough and the uppermost section having a shoulder in its slot; means at the top and bottom of the sections for engaging one section with another to prevent rotation and a locking screw passing through the sections and having a flange to seat on the shoulder in the slot of the uppermost section and the lower end of the screw entering the threaded bore in the base section. 110 115 120

10. A sectional post for loose leaf binders comprising a base section having a threaded bore therein, a series of post-sections each having a vertical opening extending therethrough and each section having means at its upper and lower sides for engaging with the next section above and below it to prevent rotation of one section with respect to another and means for locking the base and post sections together. 125 130

11. In a loose leaf binder the combination with two clamping bars, of sectional posts extending between said bars, sectional pins also extending between said bars and said posts and pins each having headed screws therein and passing through the several sections to clamp the sections together.
12. A sectional pin for loose leaf binders comprising a tubular base having internal

screw-threads, sleeves of uniform internal 10 and external diameter with the external diameter the same as that of the tubular base and a screw passing through the sleeves and having a head whose external diameter is uniform with the external diameter of the 15 sleeves and the tubular base.

In testimony whereof I affix my signature.

JOSEPH M. GARDINER.
